PORTRABLE WATER CLOSET WITH VALVED BOWL
 Kenneth A. Milette, 16110 Lear Court, Valinda, and Forrest B. Doud, 3237 Minnesota Ave., Costa Mesa, Calif.
 Filed Jan. 3, 1964, Ser. No. 335,578
 14 Claims. (Cl. 4—78)

This invention relates to a portable toilet and, more particularly, a portable toilet suitable for use in vehicles such as house trailers, campers and the like.

The invention is directed to certain needs that have become more pressing with the rapid rise in the use of vehicles for habitation.

One general need is for a toilet that is sufficiently versatile to serve, on the one hand, as a portable toilet for use in cross-country traveling and, on the other hand, to serve as a substantially permanent toilet installation when the vehicle is used at one location for an extended period of time. This need is met by a self-contained toilet structure that is inherently light enough at its maximum liquid load to be lifted and carried by a person of moderate strength and yet is adapted for releasable attachment to a permanent sewer connection. Such a toilet may be emptied at service stations when used in traveling but, nevertheless, may serve as a permanent conventional toilet on long stops.

To meet this need, the toilet is constructed largely of plastic for saving in weight and the volume of the required water supply for the self-contained toilet unit is minimized to the required degree by highly efficient utilization of the water. One feature in this regard is a highly effective hand operated means for flushing the toilet bowl and another feature is an arrangement for providing the toilet bowl with a water seal that employs a minimum quantity of water.

Another need is to minimize the likelihood of such a portable toilet getting out of order and becoming unusable. The invention affords a number of features which taken together meet this need.

One of these features is that the basic closure mechanism for controlling the outlet from the toilet bowl is extremely simple and comprises only two moving parts, namely, a dump pan that normally retains water for a gas seal and a simple pull rod for manual operation of the dump pan. Another feature is a yielding construction of the dump pan to prevent jamming of the mechanism by solid obstacles. For this latter purpose the dump pan is of thin, flexible construction to yield to an obstacle by flexure and the dump pan is further pivotally mounted in a floating manner for additional yielding action when additional yielding action is required.

Another feature for meeting the problem of mechanical breakdown relates to the hand pump that is used for flushing the toilet bowl. A hand pump necessarily adds moving parts, including a piston and two valves, to increase the vulnerability to breakdown and, moreover, repair of such a pump may require time and unusual skill. To meet this situation an efficient but inexpensive plastic hand pump is employed and provision is made for quickly and conveniently replacing the pump. Thus it is cheaper to replace such a pump than to repair it and trouble in this direction may be eliminated simply by carrying a spare pump.

The features and advantages of the invention may be understood from the following detailed description and the accompanying drawings.

In the drawings, which are to be regarded as merely illustrative:

FIG. 1a is a side elevation of a house trailer with a portion broken away to show how the toilet may be connected to a sewage outlet;

FIG. 1b is a perspective view of the presently preferred embodiment of the invention;

FIG. 2 is a top plan view of the toilet unit;

5 FIG. 3 is a vertical sectional view taken along the diagonal angular line 3—3 of FIG. 2 showing the working parts and their normal positions when the unit is not in use;

FIG. 4 is a similar view showing the dump pan retracted and showing the hand pump in use; and

10 FIG. 5 is an enlarged fragmentary section along the line 3—3 of FIG. 2 showing the construction of the flushing nozzle of the hand pump.

As shown in FIG. 1b the presently preferred embodiment of the invention is in the form of a rectangular tank or receptacle having a front wall 10, two opposite side walls 12, a back wall 14 and a top wall 15. The interior of the tank is divided by a diagonal partition 18 (FIG. 2) into a relatively small fresh water reservoir 20 and a relatively large waste compartment 22.

15 The fresh water reservoir 20 is provided with a fill opening in the top wall 15 that is normally closed by a removable plug 24 and the waste compartment 22 is provided with two discharge outlets, one being a lower outlet in the back wall 14 that is normally closed by a suitable removable plug 26 (FIG. 3), the other outlet being an outlet in the right side wall 12 above the liquid level in the waste tank, which outlet is normally closed by a removable plug 28. The lower back outlet is adapted for connection by a fitting 30 with a spare flexible outlet pipe 32 that is shown in phantom in FIG. 2. The 20 upper side outlet that is normally closed by the plug 28 is used for manually dumping the contents of the waste compartment 22.

It is contemplated that the weight of the toilet unit 35 including the maximum amount of water in the reservoir 20 will be relatively light to make the unit truly portable. For this purpose nearly all of the parts including the tank itself are preferably made of a suitable plastic which may be reinforced by embedded glass fibers. Suitable 40 handles (not shown) may be provided for convenience in lifting and carrying the unit.

The top wall 15 of the unit in the region of the waste compartment 22 is molded to offset configuration to form a toilet bowl 34 having a downwardly concave bottom wall 35 that is preferably of spherical curvature and is 45 provided with a suitable discharge outlet or port 36. A conventional seat member 38 and a seat cover 40 are mounted on the top wall 15 over the toilet bowl 34, both the seat member and the seat cover being mounted by a common hinge fitting 42 in a well known manner.

50 What may be termed a dump pan 45 made of thin flexible plastic is normally positioned below the discharge port 36 close to the bottom wall of the toilet bowl as shown in FIG. 3. The dump pan 45 is of generally or approximately spherical curvature with its circumferential rim 46 well above the discharge port 36 so that the dump pan may retain a small body of water 48 to serve as a gas seal for the discharge port.

It is important to note that the location of the discharge port 36 is off center, all or at least most of the discharge port being located to one side of a vertical plane that is indicated by dotted lines 50 in FIGS. 2 and 3. As indicated in FIG. 2 the vertical plane 50 is diagonal with respect to the seat of the toilet, the plane extending from the left front of the seat to the rear right, the discharge port 36 of the toilet bowl being on the rear side of the plane.

70 The dump pan 45 is suitably adapted for manual operation between the normally closed position shown in FIG. 3 and the dumping position shown in FIG. 4. For this purpose the dump pan is suspended from a transverse pivot axis 52 (FIG. 3) that intersects the center of cur-

ture of the dump pan and lies in the plane 50. In the construction shown, the dump pan 45 is formed with integral wings 54 that extend upward on its opposite sides, the two wings being apertured to journal on a pair of trunnions that are fixedly mounted on the outer wall of the toilet bowl 34.

In the construction shown, the pair of wings 54 are confined by corresponding washers 56 (FIG. 2) which back against cotter pins 58 on the ends of the two trunnions. It is important to note that the two washers 56 are spaced far enough apart to give the dump pan 45 a useful degree of freedom of movement along the axis of the two trunnions. Thus the dump pan 45 is yieldable in two respects to avoid being jammed by solid objects at the discharge port 36, the dump pan being made of thin flexible plastic for flexure for yielding action in one respect and being slidable on the two trunnions 55 for yielding action in another respect.

The dump pan 45 may be adapted for manual operation in any suitable manner. A feature of the present embodiment of the invention is a simple operating mechanism which includes an ear 60 on the dump pan and a pull rod 62 that is pivotally connected to the ear. The pull rod 62 is provided with a suitable knob 64 to serve as a handle and the pull rod extends through a suitable elastomeric sealing grommet 65 in the top wall 15 of the tank. To provide the required pivotal connection with the ear 60, the pull rod 62 extends through an oversized aperture in the ear and the ear is confined between a pair of washers 66 that back against corresponding cotter pins 68.

One advantage of the geometry of the arrangement based on the diagonal positioning of the two trunnions 55 is that the knob 64 for operating the dump pan is placed at a forward position of maximum convenience for operation. Another important advantage of the geometry is that the off center location of the discharge port 36 of the toilet bowl greatly shortens the stroke of the pull rod 62 that is necessary to completely uncover the discharge port 36. It can be seen in FIG. 4 that if the discharge port 36 were in a central bottom position, it would be necessary to retract the dump pan 45 much further to clear the discharge port.

A feature of the preferred embodiment of the invention is the provision of a wiper 70 for the dump pan 45, which wiper may be in the form of a plastic angle member bonded to the curved bottom wall 35 of the toilet bowl, the lower edge of the flange of the angle member conforming to the curvature of the inner surface of the dump pan. It is apparent that when the dump pan 45 is shifted from its normal closed position shown in FIG. 4, the wiper 70 displaces material from the surface of the dump pan into the waste compartment 22.

A further feature of the preferred embodiment of the invention is the provision of suitable means to serve as a splash guard to keep the small body of water 48 in the dump pan from being lost by splashing into the waste receptacle 22 when the toilet unit is joggled by a vehicle in which it is carried. The splash guard may consist of a ring 72 formed by an angular plastic member, the ring being bonded to the under surface of the curved bottom wall 35 of the toilet bowl in a position that is close to the peripheral rim 46 of the dump pan 45, the splash guard extending close to the surface of the dump pan to retain the body of water.

Any suitable manually operable means may be provided to discharge water from the fresh water reservoir 20 into the toilet bowl 34 for the purpose of flushing out the toilet bowl. In the construction shown in the drawings, an inexpensive but efficient plastic hand pump, generally designated 75 is provided, the hand pump having a cylindrical barrel 76 equipped with an intake valve 78 and an intake tube 80. Slidable in the cylindrical barrel 76 is the usual piston 82 mounted on a piston rod 84 that has a knob 85 at its outer end to serve as a pump

handle. The piston 82 has the usual valve which may be a flapper valve 86.

The upper end of the pump barrel 76 is provided with a lateral discharge spout 88 on which is mounted a plastic nozzle 90 that extends under the seat member 38 into the interior of the toilet bowl 34. As shown in FIG. 5, the pump nozzle 90 is of tapered tubular configuration with its outer end closed by an end wall 92. The outer end of the pump nozzle 90 is provided with three jet openings or orifices in the tubular wall comprising two opposite longitudinal side slots 92 and a bottom orifice 94. The two side slots 92 direct two corresponding jets of water diagonally downward in opposite directions, the two streams being indicated by dotted lines 95 in FIGS. 2 and 4.

Because of the spherical configuration of the bottom of the toilet bowl, the two streams 95 sweep around towards the opposite side of the toilet bowl as indicated by the dotted lines in FIG. 2 and meet to combine to form a single resultant downstream that is highly effective for flushing material through the discharge port 36. The bottom orifice 94 of the pump nozzle cooperates by creating a thin fan-shaped jet of water indicated at 96 in FIGS. 2 and 4 to wash the area of the inner surface of the toilet bowl that is missed by the two divergent streams 95.

A feature of the invention is the manner in which the hand pump 75 is mounted on the unit for highly convenient removal and replacement. The hand pump is retained simply in a frictional manner by an elastomeric grommet 98 that grips the pump barrel 76 in a substantially fluid tight manner. When it is necessary to replace the pump, it is merely necessary to lift the seat member 38 and pull the pump free from the grommet 98. It is seldom necessary to replace the pump nozzle 90 but the pump nozzle may be united with the pump for replacement along with the pump.

The manner in which the toilet unit serves its purpose will be readily understood from the foregoing description. When the toilet is not in use, the movable parts are normally in the positions shown in FIG. 3. To flush the toilet, the pull rod 62 is elevated by means of the handle 64 to retract the dump pan 45 to its open position shown in FIG. 4 and the handle 85 of the hand pump is operated to discharge water into the toilet bowl. As the dump pan 45 retracts it is effectively wiped by the wiper 70. At the end of the flushing operation, the dump pan 45 is returned to its normal position and the hand pump is operated to deliver additional water to the toilet bowl to fill the dump pan. When the toilet unit is carried by a traveling vehicle, a splash guard 72 effectively confines the body 48 of sealing water in the dump pan.

The toilet unit is light enough to be lifted and carried by virtue of the lightweight of the structure and by virtue of the capacity limit of the fresh water reservoir 20. The toilet unit may be easily lifted and carried to any convenient permanent toilet where the plug 28 is removed to permit the waste compartment 22 to be emptied. The fresh water reservoir 20 may then be replenished through the fill opening that is closed by the plug 24. It is to be noted that the two elastomeric grommets 65 and 98 associated with the pull rod 62 and the pump barrel 16, respectively, are effective to keep the liquids confined in the tank when the toilet unit is joggled by a traveling vehicle and when the unit is tipped over for the purpose of emptying the waste compartment 22.

If the vehicle is to remain for an extended period of time at a location where a sewage outlet is available, the previously mentioned spare flexible pipe 32 that is shown in phantom in FIG. 2 may be connected to the waste receptacle for the purpose of placing the waste receptacle into communication with a sewer, as indicated in FIG. 1a.

Our description in specific detail of the selected embodiment of the invention will suggest various changes, substitutions and other departures from our disclosure within the spirit and scope of the appended claims.

We claim:

1. In a toilet of the character described, the combination of:
a toilet bowl with a downwardly convex bottom wall and a discharge port therein;
a downwardly convex dump pan normally positioned below the discharge port with the entire periphery of the dump pan above the level of the discharge port to contain water to form a gas seal for the port;
means to support the dump pan for movement about a transverse axis located at a level substantially above the bottom wall;
the discharge port being located towards one side of a vertical plane through the axis;
means to swing the dump pan about the axis towards the opposite side of the vertical plane to clear the discharge port;
and means to flush the bowl through the discharge port.
2. A combination as set forth in claim 1 in which the dump pan is concentric to the axis; and
in which means projects downward from the bowl to wipe the dump pan in response to the retraction of the dump pan from the discharge port.
3. A combination as set forth in claim 1 in which means projects downward from the bowl towards the dump pan at the normal position of the dump pan to block spillage from the dump pan when the toilet is transported in a vehicle.
4. A combination as set forth in claim 1 in which said transverse axis is positioned diagonally of the toilet bowl as the toilet bowl is viewed in plan;
in which the swinging of the dump pan to clear the discharge port is forward towards one side of the toilet bowl; and
in which the means to swing the dump pan is manually operable means positioned forward towards said one side of the toilet bowl.
5. A combination as set forth in claim 1 in which said means to flush the bowl through the discharge port is located towards said one side of the vertical plane.
6. A combination as set forth in claim 1 in which said discharge port is offset rearwardly as the toilet bowl is viewed in plan.
7. A combination as set forth in claim 6 in which the flushing means is located above the discharge port and directs water downward towards the discharge port.
8. In a toilet of the character described, the combination of:
a toilet bowl with a downwardly convex bottom wall and a discharge port therein;
a downwardly convex dump pan normally positioned below the discharge port with the entire periphery of the dump pan above the level of the discharge port to contain water to form a gas seal for the port;
means to support the dump pan for movement about a transverse axis located at a level substantially above the bottom wall;
means to swing the dump pan about the axis to a position to permit discharge of the contents of the bowl through the discharge port, the dumping pan being concentric to the axis;
means to flush the bowl through the discharge port; and
means projecting downward from the bowl towards the dump pan at the normal position of the dump pan to block spillage from the dump pan when the toilet is transported in a vehicle.
9. In a toilet of the character described, the combination of:

- a toilet bowl with a downwardly convex bottom wall and a discharge port therein;
a downwardly convex dump pan normally positioned below the discharge port with the entire periphery of the dump pan above the level of the discharge port to contain water to form a gas seal for the port;
means to support the dump pan for movement about a transverse axis located at a level substantially above the bottom wall;
means to swing the dump pan about the axis to a position to permit discharge of the contents of the bowl through the discharge port, the dumping pan being concentric to the axis;
means to flush the bowl through the discharge port; and
means projecting downward from the bowl to wipe the dump pan in response to the swinging movement of the dump pan.
10. In a toilet of the character described, the combination of:
a toilet bowl with a downwardly convex bottom wall and a discharge port therein;
a downwardly convex dump pan normally positioned below the discharge port with the entire periphery of the dump pan above the level of the discharge port to contain water to form a gas seal for the port;
means to support the dump pan for movement about a transverse axis located at a level substantially above the bottom wall;
means to swing the dump pan about the axis to a position to permit discharge of the contents of the bowl through the discharge port;
a nozzle extending into the bowl at an upper level thereof to flush the bowl; and
a hand pump to deliver water to the nozzle, the nozzle being a tubular member closed at its outer end with two opposite orifices in the tubular wall near its outer end directed downwardly in opposite directions to form two divergent streams of water to flush the major portion of the bowl, the nozzle having a third downwardly directed orifice in its tubular wall near its outer end to flush the inner surface of the bowl in the region between the two opposite streams.
11. In a toilet of the character described, the combination of:
a tank having a relatively large compartment for wastes and having a compartment for fresh water;
a bowl incorporated into the top of the tank, the bowl having a downwardly convex bottom wall with a discharge port therein;
a downwardly convex dump pan normally positioned below the discharge port with the entire periphery of the dump pan above the level of the discharge port to contain water to form a water seal for the discharge port;
means to support the dump pan for movement about a transverse axis located at a level substantially above the bottom wall;
means to swing the dump pan about the axis to a position to permit the contents of the bowl to be discharged through the discharge port;
a hand pump extending into the fresh water compartment, the pump having an upper lateral nozzle directed into the bowl to flush the bowl, the fresh water compartment being closed with a top wall with an opening therein to receive the pump, the opening having a resilient rim to embrace the pump below the nozzle in a sealing manner for frictional retention of the pump;
the tank, bowl and pump being of light weight and the fresh water compartment being relatively small to limit the liquid content of the tank to make the tank with the liquid therein light enough to be lifted, carried and dumped by a person of average strength.

12. In a toilet of the character described, the combination of:
- a tank having a relatively large waste compartment and having a second compartment for fresh water;
- a bowl incorporated into the top of the tank, the bowl having a downwardly convex bottom wall with a discharge port therein;
- a downwardly convex dump pan normally positioned below the discharge port with the entire periphery of the dump pan above the level of the discharge port to contain water to form a gas seal for the port;
- means to support the dump pan for movement about a transverse axis located at a level substantially above the bottom wall;
- the discharge port being located towards one side of a vertical plane through the axis;
- means to swing the dump pan about the axis towards the opposite side of the vertical plane to clear the discharge port;
- means projecting downward from the bowl to wipe the dump pan in response to the swinging movement of the dump pan;
- means projecting downward from the bowl towards the dump pan at the normal position of the dump pan to block spillage from the dump pan; and
- means including a hand pump to transfer water from the fresh water compartment to the bowl to flush

the bowl through the discharge port into the waste compartment, the tank, bowl and pump being of light weight and the fresh water compartment being relatively small to limit the liquid content of the tank to make the tank with the liquid therein light enough to be lifted, carried and dumped by a person of average strength.

13. A combination as set forth in claim 12 in which the dump pan is made of highly flexible material for yielding deflection to avoid jamming of the dump pan by objects caught between the dump pan and the bowl.

14. A combination as set forth in claim 13 in which the dump pan is free to shift along the axis to yield to objects caught between the dump pan and the bowl to avoid jamming of the dump pan by objects caught between the dump pan and the bowl.
